[57] CLAIM

The ornamental design for commode or similar article, substantially as shown and described.

DESCRIPTION

FIG. 1 is a perspective view of the inventive commode
or similar article;

FIG. 2 is a right-side end view of the commode illustrated in FIG. 1;

FIG. 3 is a rear view of the commode illustrated in FIG. 1; and

FIG. 4 is a top plan view of the commode illustrated in
FIG. 1.

The side of the commode not illustrated is similar to that side which is shown.
